(57) **CLAIM**

The ornamental design for a Rogowski coil, as shown and described.

DESCRIPTION

1. Rogowski coil

1.1: is a top, front, left side Perspective view of a Rogowski coil showing my new design;

1.2: is a bottom, front, left side Perspective view thereof;

1.3 is a top, rear, right side Perspective view thereof;

1.4 is a Front elevation view thereof;

1.5 is a Back elevation view thereof;

1.6 is a Top plan view thereof;

1.7 is a Bottom plan view thereof;

1.8 is a Left side view thereof; and

1.9 is a Right side view thereof.

In views 1.1 to 1.8 one cable end is not represented in its entirety.
